UNITED STATES PATENT OFFICE.

JESSE C. MARTIN, JR., OF SAN FRANCISCO, CALIFORNIA.

LUBRICANT CARTRIDGE AND METHOD OF FILLING LUBRICANT COMPRESSORS BY MEANS THEREOF.

Application filed February 12, 1923. Serial No. 618,641.

To all whom it may concern:

Be it known that I, JESSE C. MARTIN, Jr., a citizen of the United States, residing at San Francisco, in the county of San Francisco and State of California, have invented certain new and useful Improvements in Lubricant Cartridges and Methods of Filling Lubricant Compressors by Means Thereof, of which the following is a specification.

10 The invention relates to a receptacle for lubricants, and has as an object the provision of a simple and inexpensive form of receptacle that may be readily applied to a grease gun or compressor of ordinary type

15 for the purpose of filling the compressor, and may be quickly removed from the compressor when empty, or if only partly empty after usage, because of its novel construction, may be capped and laid away for

20 further use.

A further object of the invention is the provision of a lubricant tube or cartridge in which grease, non-fluid oil, or the like, may be packaged for distribution and sale

25 and which after being once used may on account of its cheapness be discarded; a further object of the invention is the provision of a package for grease which will be clean to use, cheap to manufacture, and

30 which will prevent contamination of the grease by grit or foreign matter until the grease is placed in the compressor for delivery to the bearings; a further object of the invention is the provision of a process of

35 filling grease guns which avoids any possibility of smearing the hands of the user and which may be practiced with great convenience.

Illustrative embodiments of the article

40 provided by the present invention are shown in the accompanying drawings, in which—

Figure 1 is a side elevation of a completely filled lubricant tube partly in section showing the tube with piston end and capped end

45 as prepared in commercial form for packing and shipment in accordance with the principles of my invention.

Figs. 2 and 3 are a side and end elevation, respectively, of a stick or pusher rod used for extruding the lubricant from the tube.

Fig. 4 is a side elevation of a lubricant compressor partly in section with compressor screw and piston clear down and ready to be filled with lubricant upon removal of screw cap on barrel.

Fig. 5 shows a longitudinal section of the lubricant tube jointed against the open end of the compressor barrel, the barrel being shown partly in longitudinal section and full of lubricant, the complete charge of 60 lubricant in the tube having been pushed out of the tube into the compressor by the pusher rod, which is shown in full and resting in the tube.

Fig. 6 is a sectional view taken on line 65 6, 6, Fig. 5.

Fig. 7 shows a longitudinal section of the lubricant tube jointed against the open end of the compressor barrel, the barrel being shown partly in longitudinal section and 70 about half full of lubricant, as denoted by cross section of same, before the application of the lubricant tube, and completely filled with new lubricant extruded from the tube into the barrel against the old lubricant, the 75 pusher rod being shown in full in position in the tube.

Fig. 8 is a longitudinal section of the lubricant tube as removed from the filled compressor barrel of Fig. 7, the open end of 80 the tube being capped or covered.

Fig. 9 is a longitudinal section of a complete lubricant compressor assembled with the filled compressor barrel of Fig. 7.

The compressor as illustrated in the drawings comprises a tubular barrel 10 having one end closed, being provided with means for attachment to the part to be lubricated thereby in a well known manner.

The filling end of the gun as shown comprises a screw threaded extremity 11 upon which a cap 12 is adapted to engage. The cap 12 is provided with an opening 13, internally screw threaded to receive the screw-threaded stem 14 of a rod carrying a piston 15 provided with a cup leather 16 to make a tight joint with the interior of the barrel 10 of the gun. A handle is shown at 17 for revolution of the stem 14, all as is commonly found in practice.

A cheap tube is shown in the form of a shell 18, preferably formed of paper or straw-board which has an external diameter substantially equal to the internal diameter of the barrel 10. The length of the cartridge 105 18 is preferably such that its contents will be the same as, or slightly less than sufficient to fill, the barrel 10. One end of the tube 18 is provided with a piston or plunger 19 forming a tight closure therefor, pref- 110

erably made of wood or other inexpensive material. The tube 18 is completely filled with grease or other lubricant against the piston 19, to its opposite open end, where 5 the cap 20 of tin or pressed paper material, preferably dome shaped to better house the end of the tube after use, fits over the end of the tube 18 to prevent the exit of lubricant therefrom. A slot or recess 21 is provided at the capped end of the tube 18, this slot forming a vent upon application of the tube 18 to the compressor barrel 10, to remove the air therefrom and permit of ready filling of the barrel without the latter being 10 coming air bound during a filling operation. A rod or pusher of inexpensive wood material shown in the present instance as turned, although it may be milled rectangular or square in section to effect cheapness, is provided of size to readily fit in tube 18, without binding, and of length so that when the piston 19 is pushed to the extreme end of the tube 18 by the rod 22, the end of the rod will be substantially flush with the 15 end of the tube, while the piston 19 will extend beyond the opposite end of the tube a short distance, as indicated in Fig. 5, to entirely clear the tube of lubricant and yet not push the piston 19 through the tube into the lubricant of the compressor barrel so that 20 it is required to be removed by the hands, which is particularly objectionable on account of smearing grease on the hands of the user. The piston 19 is also set in a 25 short distance from the end of the tube 18, as at 23, when the grease or lubricant is filled therein, acting as a starter or guide for the introduction of pusher rod 22.

In the practice of my invention the tube 40 18 is preferably made of such a diameter that upon the introduction of its open lubricant end into the open end of the compressor 10, a joint is formed as at 24, Figs. 5 and 7, by the slight compression of the paper or 45 fibre tube against the harder or metallic compressor barrel, although it is obvious that other joint means between the end of the grease tube and compressor can be made equally satisfactory, without departing from 50 the principles of the invention. The presence of the slot 21 assists in permitting the slight compression of the tube, thereby furthering the formation of a tight joint at 24.

By the formation of a joint between the 55 tube and the compressor barrel the lubricant extruded or pushed from the tube into the compressor barrel is prevented from passing back to waste, overcoming any smearing of the operator's hands, eliminating expense 60 in lubricant wastage, as well as saving time in cleaning both tube and compressor barrel after a filling operation. In the practice of the present form of my invention as shown in Figs. 5 and 7, during a filling operation, 65 the tube 18 is pressed into the barrel 10, and

the pusher rod 22 is brought against the piston 19. By now moving the piston with the rod the lubricant is forced out of the tube 18 into the compressor barrel 10, and as the lubricant enters the barrel the air in 70 the barrel is forced out through the vent 21. It will be noted that the vent 21 is made to communicate with the interior of the barrel. The oncoming grease continues to fill the barrel while the air is expelled until the 75 barrel is finally full, the grease or lubricant being brought against the end of the tube, at which time upon further movement of piston 19, by pusher rod 22, the pressure of the lubricant breaks the joint between the 80 tube and the compressor barrel by pressure against the annular end of the tube, and the tube is withdrawn from the filled compressor barrel. The loosening of the tube from the 85 barrel is readily noticeable in the hands of the operator.

It will be noted that in the present form of compressor barrel illustrated, the joint at 23 between the tube and barrel is made a short distance from the end on the inside 90 of the barrel. This provides that upon removal of the tube a clearance or space in the end of the barrel is formed, permitting the piston 19 of the compressor to readily enter without the necessity of grease 95 removal from the barrel, which is wasteful and objectionable to the user. It is also desired to point out that in some forms of lubricants, through their relatively higher viscosity, upon removal of the tube 18 from barrel 10, a slight amount of lubricant is brought away on the end of the tube, as shown in Fig. 8, and for this reason the domed cap 20 is preferably provided as a 100 cover, not necessitating that the operator touch the end of the grease tube which would smear grease on his hands even if he did not desire to scrape off this small amount of surplus grease into the clearance end of the compressor barrel, as provided for the compressor piston 19. The lubricant tube 10 can be conserved and used over again if desired, being made relatively cheap but substantial for the service. In such case refilling of the tubes is accomplished by pushing the piston 19 back to its original end of the tube by pusher rod 22, inserting the lubricant as originally and capping the end of the tube with cover 20, in the manner 110 shown in Fig. 1.

Minor changes may be made in the physical embodiment of the invention without departing from its spirit.

What I claim is:

1. A lubricant cartridge for filling a 125 grease gun comprising, a cylinder having an internal diameter less than that of the grease gun and an external diameter at one end slightly greater than the internal diameter of the grease gun to be filled, said 130

end being compressible whereby it may be forced, a short distance only in comparison with its total length, within the end of the gun forming a tight joint therewith, the 5 internal diameter of the cylinder being such that the slug of lubricant extruded may allow air to escape past the same, and vent means carried by the engaging end of the cartridge to permit escape of air from the 10 gun during the filling operation.

2. A lubricant cartridge for filling a grease gun comprising a cylinder having an internal diameter less than that of the grease gun and an external diameter at one end 15 slightly greater than the internal diameter

of the gun to be filled, said end having a venting slot at the surface to be engaged with the gun whereby to make the said end more readily compressible and to vent air from the gun during the filling operation, 20 the diameter of the end of the cylinder and its capability to be compressed being such as to be adapted to enter slightly within the end of the gun and form a tight joint therewith, and the internal diameter of the cylinder being such that the slug of lubricant extruded may allow air to escape to the vent. 25
